MULTIPOLE CIRCUIT BREAKER

Paul M. Christensen, West Orange, N. J., and Alexander R. Norden, New York, N. Y., assignors to Federal Electric Products Company, Newark, N. J., a corporation of Delaware

Application August 24, 1950, Serial No. 181,224

25 Claims. (Cl. 200—116)

1

This invention relates to multi-pole circuit breakers and to tripping and actuating devices therefor. More particularly, but without restriction, the invention is related to multi-pole circuit breakers of the general type disclosed in the copending application of Paul M. Christensen, Ser. No. 181,223 filed August 24, 1950, assigned to the assignee hereof, and is concerned with a multi-pole circuit breaker which can be manually opened and closed and which is also opened automatically at all of the poles upon the occurrence of an overload in the circuit at any one of the poles.

In general, the individual circuit breaker mechanisms are of the type disclosed in U. S. Patents Nos. 2,174,669, 2,209,319, 2,209,352, 2,209,353, Re. No. 23,188 and the copending applications of Thomas M. Cole, Ser. No. 127,433, filed November 15, 1949, now Patent No. 2,647,186, and Ser. No. 184,749, filed September 14, 1950, both assigned to the assignee hereof.

The primary object of the present invention is the provision of a multi-pole circuit breaker of the above mentioned type, which is of generally improved operation and construction.

Another object is the provision of a multi-pole circuit breaker which is opened automatically at all of the poles thereof upon the occurrence of an overload in the circuit at any one pole and which is automatically reset, upon the tripping thereof, for manual movement to the closed condition thereof, without the necessity of a separate resetting operation.

The present invention will be fully understood from the following description considered in connection with the accompanying drawings illustrating the presently preferred embodiment of the invention.

In the drawings:

Fig. 1 is a side view of a circuit breaker embodying the present invention;

Figs. 2 and 3 are end views as seen from the lines 2—2 and 3—3, respectively, of Fig. 1;

Fig. 4 is a top view of the circuit breaker;

Fig. 5 is a view similar to Fig. 1, one part of the housing being removed, the circuit breaker mechanism being closed or in circuit making condition;

Fig. 6 is a sectional view taken on the line 6—6 of Fig. 5;

Fig. 7 is a sectional view taken on the line 7—7 of Fig. 5;

Fig. 8 is a sectional view taken on the line 8—8 of Fig. 6;

Fig. 9 is a sectional view taken on the line 9—9 of Fig. 6;

2

Fig. 10 is a sectional view taken on the line 10—10 of Fig. 5;

Fig. 11 is a sectional view taken on the line 11—11 of Fig. 6;

Fig. 12 is a sectional view taken on the line 12—12 of Fig. 6;

Fig. 13 is a sectional view taken on the line 13—13 of Fig. 6;

Fig. 14 is a sectional view taken on the line 14—14 of Fig. 6;

Fig. 15 is a sectional view taken on the line 15—15 of Fig. 5;

Fig. 16 is a fragmentary sectional view taken on the line 16—16 of Fig. 5;

Fig. 17 is a fragmentary sectional view taken on the line 17—17 of Fig. 5;

Fig. 18 is a partial view similar to Fig. 5 showing the circuit breaker mechanism in the open condition thereof;

Fig. 19 is a fragmentary sectional view taken on the line 19—19 of Fig. 18;

Fig. 20 is a view similar to Fig. 18 showing another position of the circuit breaker mechanism in the open condition thereof;

Fig. 21 is a fragmentary sectional view taken on the line 21—21 of Fig. 20; and

Fig. 22 is a fragmentary sectional view taken on the line 22—22 of Fig. 21.

Referring to the drawings in detail, the circuit breaker of the present invention comprises a housing 30 formed by the casings 32 and 34, each of which houses a separate circuit breaker mechanism. Casing 32 comprises the body part 36 provided with the cover 38, and casing 34 comprises the body part 40 and the cover part 42, all of said parts being preferably molded from any suitable plastic, for example, "Bakelite." The casings 32 and 34 are secured together in laterally disposed relation in any suitable manner, as by the bolts 44 which extend through both casings, as illustrated in Figs. 1, 3 and 18, the surface of cover part 42 facing outwardly of casing 34, being provided with the raised portions 46 which are received in complementary surface recesses 48 defined in body part 36 of casing 32, as illustrated in Figs. 6, 7, 10, 15, 19 and 21.

In the illustrated embodiment of the invention, the circuit breaker is of the "plug-in" type for use with a terminal plate assembly such as that described in application Ser. No. 127,432 filed November 15, 1949, by Thomas M. Cole and Paul M. Christensen, as joint inventors and assigned to the assignee hereof. It will be understood, however, that the present invention is not limited to plug-in circuit breakers but is applicable as well to circuit breakers which are not provided

with plug-in terminals. The casings 32 and 34 are provided, at one end thereof, with an open recess 50 formed in the respective body parts, and adapted to engage a hooked element of the terminal plate assembly. At its other end, each of said casings is provided with a re-entrant lower portion 52 formed in both the body parts and the cover parts thereof, and adapted to encompass the side and a portion of the top surface of a contact block unit of said terminal plate assembly when mounted thereon. Each casing is provided, above the re-entrant portion 52 thereof, with a chamber 54 in which there is vertically mounted a plug-in terminal prong or stab contact 56 for making contact with said terminal block unit. Said contact 56 is provided with the laterally extending portions or arms 57 which are removably positioned in cooperating recesses 59 formed in the walls of said chamber. It will be understood that the described mounting means and the stab contact, per se, do not form part of the invention to which this application is directed and that the housing 36 may be otherwise mounted in any suitable manner.

Each casing is provided, above the open recess 50 therein, with an arcing chamber 58 in which the stationary contact 60 and movable contact 62 are disposed for relative movement. It will be noted that said arcing chambers are each bounded by the similarly thickened portions 61, 63 and 64 of the body parts 36 and 40, respectively, and by the portions 66 of said body parts which are of reduced thickness and which extend between the portions 63 and 64 thereof. It will be noted that portion 64 is provided with a shoulder 68 where it extends above portion 66 and that portion 63 is provided with an angular step 70 where it extends above said portion 66. The cover parts 38 and 42 are each provided on its surface, which faces its companion body part, with a thickened portion 72 (Figs. 9, 12 and 16) which is complementary in form to the portion 66. When the cover and body parts of casings 32 and 34 are in housing-defining relation, the ends 74 and 76 of said portion 72 abut the step 70 and the shoulder 68, respectively, as illustrated in Fig. 16, and said portion together with portion 66, the confronting surfaces of which are spaced as at 78, form a bounding wall for the arcing chamber in opposition to the wall thereof formed by the thickened portion 61. Therefore, it will be noted that each casing is provided with an arcing chamber which is closed on all sides thereof except at its opening 80 externally of the casing whereby arcs which may be formed upon the disengagement of contacts 60 and 62 are to a very considerable extent prevented from entering that portion of the casing in which the circuit breaker mechanism is contained. A chamber 82 is provided in casing 32 for containing the circuit breaker mechanism 84 thereof and a similar chamber 86 is formed in casing 34 for containing the circuit breaker mechanism 88 thereof. Each of said chambers is provided with an opening 90 which extends through the body part in which said chamber is defined, a handle 92 projecting from casing 32 and a similar handle 94 projecting from casing 34. Said handles are each formed of insulation material, one of said handles, here shown as 94, being provided with a laterally extending pin 96 (Fig. 7) which is received in a companion recess 98 formed in handle 92 to provide for the conjoint operation of said handles. Handle 92 is provided with a circular pivot portion 100 which

is positioned in the bearing recess 102 formed in cover part 38, and handle 94 is provided with a similar pivot portion 104 which is positioned in the bearing recess 106 formed in the body part 40. Handle 92 is also provided with the laterally extending circular pivot portion 108 positioned in the bearing recess 110 (Figs. 7 and 10) formed in body part 36, and handle 94 is provided with a similar pivot portion 112 positioned in the bearing recess 114 formed in the cover part 42.

The circuit breaker mechanisms 84 and 88 are the same and, therefore, a detailed description of one of said mechanisms will be sufficient to describe both of said mechanisms. The circuit breaker mechanism includes a manual operable member, here shown as the above mentioned pivoted handle 92 or 94. A uniplanar movable contact member 116 is mounted in the chambers 82 and 86, respectively, for pivotal movement by pivot pin 118, the opposite ends of which are received in the aligned bearing projections 120 on the opposing surfaces of each of the casing parts of casings 32 and 34. At one end thereof the movable contact member is provided with the previously mentioned contact 62 which is engageable with and disengageable from the companion contact 60 carried by the terminal member 122 which is mounted in an open recessed portion 124 formed in each of the casings above the arcing chambers 58 thereof. As here shown, the terminal member 122 is provided with a terminal screw 126 and an extending portion 128 which extends into the chamber 58 and which carries the aforementioned contact 60. The aforementioned complementary casing portions 66 and 72 form a guideway for the movable contact member, the space 78 between the confronting surfaces thereof defining a guide slot through which an end portion 130 of the movable contact member projects with slight clearance, as illustrated in Fig. 16. It will be noted from Figs. 18 and 21 that said end portion 130 abuts the step 70 in the disengaged condition of the companion contact, said step serving to limit the movement of the movable contact member in its circuit open position.

At its end portion 130, the movable contact member is provided with an integral depending portion 132 (Fig. 16) which extends through a slot 134 at one end of a thermal-current responsive member 136 which, as here shown, consists of a thermal bi-metallic strip which is welded or otherwise secured on one end of a side edge of said movable contact member 116. The free end of bi-metallic strip 136 is arranged to releasably engage a latch element 138 at one end of an actuating member or lever 140 pivotally mounted on the end of said movable contact member 116 opposite the end thereof which carries the contact 62.

As here shown, the lever 140 is formed in one piece of sheet metal and comprises laterally spaced opposing walls 142, 142 open between the marginal edges 144, 144 thereof, and partially closed between the opposite marginal edges 146, 146 thereof, by the integral wall 148 (Fig. 6) provided with the opening 150 defined therein. The aforementioned latch 138 is provided on said wall 148 and depends below the opposing walls 142, 142 of said lever. Said walls are provided with the confronting punched-in cylindrical projections 152 (Fig. 15) which are mounted for pivotal movement in an insulated bushing 154 mounted in an aperture 156 provided in the movable contact member 116 at the aforementioned

opposite end thereof. It will be noted that said bushing is provided with portions which overlie side surface portions of the movable contact member and that one of said bushing portions is provided with a part 158 (Fig. 8) which overlies and is secured to a side edge portion of the contact member above the aperture 155 therein. It will be noted that when the lever 142 is mounted on the movable contact member 116, the walls 142 thereof straddle said movable member and the end portion 160 of said movable member projects through the opening 150 in wall 148. Each of said side walls is also provided, at the end thereof remote from the latching element 138, with a slotted portion 162 which extends transversely of said walls and which is provided at the end thereof remote from wall 148 with a constricted portion 164 which extends upwardly of the remaining portion of said slot to form a depending shoulder 166 adjacent said constricted portion. Each wall is also provided with a depending hooked element 168. Said hooked elements are provided with inturned portions 170 (Figs. 10, 15 and 21) which function as herein-after described.

Each handle is provided with an integral portion 172 which extends below the pivot portions thereof. Said portions 172 are each provided with a bearing aperture 174 (Fig. 21). A resilient link, here shown as a spiral spring member 176, is provided at one end thereof with the laterally extending pivot portions 178 which are received in the aforementioned apertures 174. Mounted within the member 176 is a floating ball or universal link 179 formed of insulated material and provided with the laterally extending portions 180 in each of which there is mounted a pin 182. To accommodate ball 179, the interlocked, abutting casing portions 36 and 42 are each apertured as at 184 and 186, respectively. It will be noted from Figs. 6, 10, 19 and 21, that the spring link 176 is disposed in said apertures, which are in registry, with the portions 180 of ball link 179 and the pins 182 carried thereby, extending outwardly of said apertures and into the casing chambers 82 and 86, respectively, for engagement with the levers 140 in said chambers, respectively. More specifically, the pin members 182 are engaged in the adjacent slots 162, and in the closed or circuit-making condition of the circuit breaker mechanism, the pin member 182 is positioned in the restricted portion 164 of the slot, the pin member being wedged between the portion 158 of bushing 154 and the shoulder 166, it being noted from Fig. 5 that the opening between the shoulder 166 and said portion 158 is narrower than the diameter of the pin 182. It will be apparent that the ball 179 and the link 176 constitute a universal joint between the handles 72 and the actuators 140.

A coil compression spring 188 is operatively interposed between the movable contact member 116 and each of the handles for biasing the movable contact member to its open position. One end of said spring engages a lug 190 carried by the handle and the other end of said spring engages a lug 192 integral with the movable contact member 116. A detent member 194 extends outwardly from the bearing projections 120 of casing parts 36 and 40, respectively, for limiting the movement of the spring 188 in the direction of the stab contact 56 when the handles are moved in the direction to close the circuit breaker mechanism.

It will be understood that thermostat mem-

ber 136 operates to latch the companion manually operable actuating mechanism 140 to the movable contact member 116 and to unlatch the actuating mechanism from the movable contact member, unlatching taking place upon deflection of member 136 causing the disengagement of end 196 thereof from the latch element 138 upon the occurrence of an overload or under other abnormal current conditions in a circuit controlled by the circuit breaker. In the closed condition of the circuit breaker, as illustrated in Fig. 5, the bias exerted by the compressed spring 188 to move the movable contact member 116 to the open position thereof, as illustrated in Fig. 18, is opposed by the tension exerted by the compressed spiral link member 176 whereby to maintain the movable contact member in the closed position thereof. More specifically, when the circuit breaker mechanism is in the open condition thereof, as illustrated in Fig. 18, the spring 176 is in the relaxed condition thereof, it being noted that the spring portions 178, which are mounted in the movable handles, are spaced from the remaining spiral portion 192. It will be noted that the pin members 182 are wedged between bushing portion 158 and shoulder 166, as previously described. When the handle is moved from the "off" position illustrated in Fig. 18 to the "on" position illustrated in Fig. 5, in addition to compressing spring 188, due to the movement of lug 190 of the handle toward portion 192 of contact member 116, the handle portion 172, in which the spring portion 178 is mounted, is moved counterclockwise from the approximately vertical disposition thereof, as in Fig. 18, toward the inclined position thereof as in Fig. 5. During said movement, since the pin members 182 are prevented from moving into slots 162 by the shoulders 166, the levers 140 are carried forwardly and downwardly whereby to latch end 196 of member 136 and the latch element 138. At the end of said movement the portion 178 of the spiral link member is positioned close to the portion 192 thereof, as illustrated in Fig. 13, to compress said spiral spring for providing a contact pressure, the tension of which spring is greater than the bias of the compressed spring 188.

It will be understood that the handle pivot 180, pivot portion 178 of spring 176 and the pin 182 constitute the centers of a toggle in each circuit breaker mechanism. In the closed condition of the circuit breakers (Fig. 5), said portion 178, which constitutes the elbow of the toggle, is disposed to the right of the center-line between pivot 180 and pin 182. In the open condition (Fig. 18), portion 178 is to the left of said center-line. In said closed condition, the bias exerted through the toggle is effective to maintain both mechanisms in closed condition, the bail link interengaging said mechanisms and being releasably retained against movement relative thereto and disposed as in Fig. 6.

Upon the occurrence of an overload, or other abnormal condition, in either circuit, the end 196 of the flexible member 136, in the overloaded circuit, flexes out of engagement with the latch 138 whereupon lever 140 rotates in a clockwise direction and horns 168 thereof frictionally engage the movable contact member 116 for slowing down the speed of motion of the lever relative to the contact member. Said rotation moves shoulder 166 out of the path of pin 182 in said circuit breaker mechanism and the pin is freed for movement into slot 162. Said movement of the pin causes the collapse of the toggle of said

mechanism, the elbow 172 thereof being carried downwardly beyond the center-line to the position of Fig. 18. As a result of the collapse of the toggle and due to the expansion of spring 183, the latter rotating the movable contact member 5 out of engagement with the stationary contact, the handle is rotated in a clockwise direction causing pin 182 to be carried back toward the constricted slot portion, the lever thereupon being rotated in a counter-clockwise direction, the horns 168 being disengaged from the movable contact member, and the lever assuming the position illustrated in Fig. 18. As a result of the foregoing movement of pin 182 in the tripped circuit breaker, the ball link 179 is free to pivot 10 as in Fig. 21. Said pivotal movement of the ball link relieves the tension of the toggle applied therethrough to the untripped circuit breaker and the spring 183 in the untripped side rotates the movable contact member and lever thereof, 15 as a unit, for disengaging the contacts in the untripped circuit breaker. It will be noted that the lever in the overloaded circuit breaker, due to the momentary engagement of the horns 168 thereof with the movable contact member, is prevented from possible reengagement with the flexible strip thereof. In this connection, it will be understood that said releasable engagement of the horns on the movable contact member serves to prevent free and uncontrolled movement of 20 the lever upon release thereof by the flexible strip. It will also be noted that due to the presence of the slots 162, the pins 182 of the ball link are free to move thereby permitting the ball link 25 to pivot in spring member 176 as a universal joint between the handles and the actuators whereupon said link may adjust itself, as required, to effect the described opening of the mechanism in the circuit which was not overloaded. In addition, it will be noted that in the 30 "off" position, both mechanisms are automatically positioned for manual resetting to the "on" position, and do not require any additional resetting operation before movement to said "on" 35 position.

The circuit breaker of the present invention is of the "trip-free" type and will trip even if the handle is retained in the "on" position. With the handle so retained, the strip 136 flexes upon occurrence of an overload in one of the circuits and upon disengagement thereof with the lever 140, spring 183 pivots the movable contact member 116 in a counter-clockwise direction to disengage contacts 60 and 62. Upon said flexing, lever 140 is freed for clockwise rotation, pin 182 moving into slot 166, and horns 168 engaging the movable contact member, as previously described. Due to said movement of the pin in the tripped circuit breaker, the ball link 179 is free to pivot, as in Fig. 21, and the tension of the toggle applied therethrough to the untripped circuit breaker is relieved, whereupon the spring 183 in the untripped side is effective to rotate the movable contact member thereof for disengaging the contacts in the untripped circuit breaker. Under normal conditions, upon release of the handle, the circuit breaker will assume the "off" position illustrated in Fig. 18. However, if the handle is retained in the "on" position long enough to permit strip 136 in the overloaded circuit breaker, to cool, the tension of spring 183 may be insufficient to carry the handle to the full "off" position, said strip preventing the full return of the companion lever 140. In the latter case, upon release of the handle, the circuit 40

breaker will assume the positions illustrated in Figs. 20 to 22. It will be noted that in said positions, the handle is short of the full "off" position thereof and the horns 168 of the lever in the overloaded circuit are in frictional engagement with the movable contact member thereof, the lever 140 in the other circuit breaker being in proper position as in Fig. 22. To reset the mechanism, prior to manual movement thereof to the "on" position, the handle is moved to the full "off" position, as in Fig. 18, to disengage the horns of the engaged lever, whereupon the circuit breaker components are all in correct position for movement of the handles to the "on" position.

The movable contact members are also provided with a general circular peripherally interrupted aperture 282 and a tapered pin 284 for calibrating the circuit breaker mechanism, it being understood that said calibrating means is effective to vary the amount of overlap of the latch element 138 at the end 198 of the flexible member 136.

The thermal member 136 is connected in series with the movable contact member 116 and the circuit which is to be controlled by the circuit breaker. For this purpose a flexible metallic conductor or connector 286 is connected to said thermal element and extends through an opening 298 in the wall portion 210 which separates the chamber containing the circuit breaker mechanism from the chamber in which the stab contact 58 is mounted, for connection to said stab contact which makes contact with the power line in the terminal panel assembly of the copending application described above.

As illustrated, the thermal current responsive member 136 is preferably operable, not only in response to the heating effect of the current passing therethrough but is also operable under the control of electromagnetic means for effecting disengagement of the companion relatively movable contacts 60 and 62, and the arrangement is preferably such that, as here shown, the electromagnetic means is energized by the current which passes through the said thermal responsive member. For this purpose an electromagnetic member 212 is fixedly secured, preferably by welding, or in other suitable manner, on member 136 near the free end thereof and a companion rigid armature 214 is disposed in spaced confronting relation to electromagnetic member 212. As shown in Fig. 7, magnetic member 212 straddles member 136 by which it is carried. Said member 212 is formed in one piece of soft sheet steel or other suitable sheet material and is provided with the depending portions 216 which are arranged in surface confronting relation to the adjacent surface of armature 214. As shown in Fig. 16, armature 214 is provided with a slotted portion 218, opposite the free end thereof, which is aligned with slot 134 in member 136. The armature is secured to the fixed end of member 136, preferably by welding, and side portions 220 thereof are bent upwardly and abut the marginal side edges of member 136, the depending portion 132 of member 116 extending through said aligned slots and being riveted to the outer surface of the armature. The electromagnetic member 212 and the armature 214 operate substantially in the same way as corresponding mechanism in U. S. Patent Re. 23,188.

While we have shown and described the preferred embodiment of our invention, it will be understood that various changes may be made

in the present invention without departing from the underlying idea or principles of the invention within the scope of the appended claims.

Having thus described our invention, what we claim and desire to secure by Letters Patent is:

1. In a multi-pole circuit breaker having a circuit breaker mechanism for each circuit, each mechanism being biased for movement from the circuit-closed condition to the circuit-open condition thereof, means inter-engaging said mechanisms and releasably retained from movement relative thereto in the circuit-closed condition thereof, said interengaging means including means operative thereupon for biasing said mechanisms in said circuit-closed condition in opposition to the first mentioned bias thereon, and means for effecting relative movement between said inter-engaging means and said mechanisms upon the occurrence of a predetermined current in one of said circuits whereby to relieve said opposing bias sufficiently for said circuit breakers to be moved to the circuit-open condition thereof.

2. In a multi-pole circuit breaker having a circuit breaker mechanism for each circuit, each mechanism being biased for movement from the circuit-closed condition to the circuit-open condition thereof, universal joint means interconnected said mechanisms and releasably retained from movement relative thereto in the circuit-closed condition thereof, toggle means operative upon said joint means for biasing said mechanisms in said circuit-closed condition in opposition to the first mentioned bias thereon, and means included in the interconnection of said universal joint and said mechanisms for effecting movement of said joint relative to said mechanisms upon the occurrence of a predetermined current in one of said circuits for operating said toggle means whereby to move said circuit breakers to the circuit-open condition thereof.

3. In a multi-pole circuit breaker having a circuit breaker mechanism for each circuit, each mechanism being biased for movement from the circuit-closed condition to the circuit-open condition thereof, resilient means, link means universally mounted in said resilient means and interconnecting said mechanisms, said resilient means and said linking means constituting a toggle, said linking means being releasably retained in predetermined disposition in the circuit-closed condition of said mechanism whereby said toggle biases said mechanism in opposition to bias thereon, and means freeing said linking means to move from said disposition thereof relatively to at least one of said mechanisms upon the occurrence of a predetermined current in the circuit of said one mechanism for operating said toggle whereby to move said circuit breakers to the circuit-open condition thereof.

4. In a multi-pole circuit breaker having a plurality of circuit breaker mechanisms each biased for movement from the circuit-closed condition to the circuit-open condition thereof and each provided with a pivotally mounted operating member, said members being joined for conjoint operation; a resilient member connected to said operating members and mounted for movement thereby to and from the operative position thereof, means mounted for universal movement by said resilient member inter-engaging said mechanisms and releasably retained from movement relative thereto in the circuit-

closed condition thereof, said resilient member when moved to the operative position thereof biasing said mechanisms through said inter-engaging means in opposition to the bias thereon, and means freeing said linking means for pivotal movement upon the occurrence of predetermined current in one of the circuits whereby to relieve said opposing bias sufficiently for said circuit breakers to be moved to the circuit-open condition thereof, said inter-engaging means comprising a ball lever mounted for universal movement in said resilient means and having laterally extending portions engageable with said mechanisms.

5. In a multi-pole circuit breaker having a pair of circuit-breaker mechanisms each having a stationary contact, a movable contact member engageable and disengageable therewith and normally biased for movement from the circuit-closed to the circuit-open condition thereof, manually operable actuating means for effecting the engagement thereof, and a control member for effecting the disengagement thereof; said actuating means comprising a lever pivotally mounted on said contact member and releasably connected thereto by said control member in said circuit-closed condition, a link mounted for universal movement and retained against said movement in the circuit-closed condition of the circuit breaker by releasable engagement between said levers, and a resilient member in which said link is mounted for biasing said mechanisms in opposition to the bias thereon, said releasable engagement of said link and said levers including lost motion connections for said movement of said link upon release of one of said levers upon the occurrence of predetermined current in the circuit of the mechanism of said one lever whereby to relieve said opposing bias sufficiently for said circuit breakers to be moved to the circuit-open condition thereof.

6. In a multi-pole circuit breaker having a pair of circuit-breaker mechanisms each having a stationary contact, a movable contact member engageable and disengageable therewith and normally biased for movement from the circuit-closed to the circuit-open condition thereof, manually operable actuating means for effecting the engagement thereof, and a control member for effecting the disengagement thereof; said actuating means comprising a lever pivotally mounted on said contact member and releasably connected thereto by said control member in said circuit-closed condition, a link mounted for universal movement and retained against said movement in the circuit-closed condition of the circuit breaker by releasable engagement between said levers, and a resilient member in which said link is mounted for biasing said mechanisms in opposition to the bias thereon, said releasable engagement of said link and said levers including lost motion connections for said movement of said link upon release of one of said levers upon the occurrence of predetermined current in the circuit of the mechanism of said one lever whereby to relieve said opposing bias sufficiently for said circuit breakers to be moved to the circuit open condition thereof, said lost motion connections comprising slotted means defined in said levers and provided with a constricted portion, said link being retained in said constricted portions in the circuit-closed condition and being released therefrom for movement into at least one of said slots upon said unlatching.

7. In a multi-pole circuit breaker having a plurality of mechanisms each having a stationary contact, a movable contact member engageable and disengageable therewith, actuating means for operatively effecting the engagement thereof and a control member for effecting the disengagement thereof in response to predetermined current in the circuit, said movable member being biased for movement from the circuit closed to the circuit open position thereof, said control member being bodily carried by said movable member and said actuating means releasably connected thereto pivotally carried thereby and being in said circuit closed condition by said control member link means mounted between said actuating means and retained against movement relative thereto in the circuit-closed condition of said mechanisms, resilient means carrying said link means for biasing said mechanisms in opposition to the bias thereon, and lost motion connections between said link means and said actuating means operable upon release of one of said actuating means by the companion control member to relieve said opposing bias for moving said mechanisms to the open condition thereof.

8. In a multi-pole circuit breaker having a plurality of mechanisms each having a stationary contact, a movable contact member engageable and disengageable therewith, actuating means for operatively effecting the engagement thereof and a control member for effecting the disengagement thereof in response to predetermined current in the circuit, said movable member being biased for movement from the circuit closed to the circuit open position thereof, said control member being bodily carried by said movable member and said actuating means being pivotally carried thereby and releasably connected thereto in said circuit closed condition by said control member link means mounted between said actuating means and retained against movement relative thereto in the circuit-closed condition of said mechanisms, resilient means carrying said link means for biasing said mechanisms in opposition to the bias thereon, and lost motion connections between said link means and said actuating means operable upon release of one of said actuating means by the companion control member to relieve said opposing bias for moving said mechanisms to the open condition thereof, said resilient means being a spiral spring member and said link means being a ball link mounted for universal movement therein.

9. In a multi-pole circuit breaker having a plurality of mechanisms each having a stationary contact, a movable contact member engageable and disengageable therewith, actuating means for operatively effecting the engagement thereof and a control member for effecting the disengagement thereof in response to predetermined current in the circuit, said movable member being biased for movement from the circuit closed to the circuit open position thereof, said control member being bodily carried by said movable member and said actuating means being pivotally carried thereby and releasably connected thereto in said circuit closed condition by said control member a universal joint mounted between said actuating means and retained against movement relative thereto in the circuit-closed condition of said mechanisms, resilient means carrying said joint for biasing said mechanisms in opposition to the bias thereon, and means freeing said joint for movement relative

to said actuating means upon release of one of said actuating means by the companion control member whereby to relieve said opposing bias for moving said mechanisms to the open condition thereof, said resilient means being a spiral spring member and said joint being a ball link mounted for universal movement therein, said ball link having laterally extending parts and said joint-freeing means being a slot defined in each actuating means and having a constricted portion, said parts being retained in said constricted portions in the circuit-closed condition and being released therefrom for movement into at least one of said slots upon said disengagement of said strip.

10. Actuating means for a multi-pole circuit breaker having a plurality of movable contact members normally biased for movement to circuit-open condition and each provided with a lever pivotally mounted thereon and carrying a flexible member in normal engagement with said lever to prevent relative pivotal movement, comprising resilient means mounted for movement to and from an operative position for biasing said movable members to circuit closed condition, and link means carried by said resilient means and normally movable relative thereto, said link means being retained by said levers against said movement in the circuit-closed condition and being released for movement upon the disengagement of a flexible member from its companion lever for relieving the bias of said resilient means whereby the normal bias of said movable members is effective to move the latter to said circuit-open condition.

11. Actuating means for a multi-pole circuit breaker having a plurality of movable contact members normally biased for movement to circuit-open condition and each provided with a lever pivotally mounted thereon and carrying a flexible member in normal engagement with said lever to prevent relative pivotal movement, comprising pivotally mounted operating means, resilient means mounted for movement thereby to and from an operative position for biasing said movable members to circuit-closed condition, and link means carried by said resilient means and normally movable relative thereto, said link means being retained by said levers against said movement in the circuit closed condition and being released for movement upon the disengagement of a flexible member from its companion lever for relieving the bias of said resilient means whereby the normal bias of said movable members is effective to move the latter to said circuit-open condition.

12. Actuating means for a multi-pole circuit breaker having a plurality of movable contact members normally biased for movement to circuit-open condition and each provided with a lever pivotally mounted thereon and carrying a flexible member in normal engagement with said lever to prevent relative pivotal movement, comprising resilient means mounted for movement to and from an operative position for biasing said movable members to circuit-closed condition, and link means carried by said resilient means and normally movable relative thereto, said link means being retained by said levers against said movement in the circuit-closed condition and being released for movement upon the disengagement of a flexible member from its companion lever for relieving the bias of said resilient means whereby the normal bias of said movable members is effective to move the latter to said

circuit-open condition, said levers each having defined therein a slot provided with a restricted portion, said link means comprising a ball member having laterally extending parts each retained in a restricted portion in the circuit-closed condition and released therefrom for movement into at least one of said slots upon said disengagement of a flexible member.

13. In a multi-pole circuit breaker having a plurality of movable contact members normally biased for movement to circuit-open condition and each provided with a lever pivotally mounted thereon and carrying a flexible member in normal engagement with said lever to prevent relative movement, the combination with said levers of resilient means mounted for movement to and from an operative position for biasing said movable members to circuit-closed condition, and link means carried by said resilient means and normally movable relative thereto, said link means being retained by said levers against positive movement in the circuit-closed condition and being released for positive movement upon the disengagement of a flexible member from its companion lever for relieving the bias of said resilient means whereby the normal bias of said movable members is effective to move the latter to said circuit-open condition.

14. In a multi-pole circuit breaker having a plurality of movable contact members normally biased for movement to circuit-open condition and each provided with a lever pivotally mounted thereon and carrying a flexible member in normal engagement with said lever to prevent relative movement, the combination with said levers of pivotally mounted operating means, resilient means mounted for movement thereby to and from an operative position for biasing said movable members to circuit-closed condition, and link means carried by said resilient means and normally movable relative thereto, said link means being retained by said levers against positive movement in the circuit-closed condition and being released for positive movement upon the disengagement of a flexible member from its companion lever for relieving the bias of said resilient means whereby the normal bias of said movable members is effective to move the latter to said circuit-open condition.

15. In a multi-pole circuit breaker, a pair of casings each adapted to contain a circuit breaker mechanism, said casings being disposed in surface abutting disposition, the abutting surfaces thereof being provided with aligned apertured portions, and means mounted for universal movement in said apertures and extending therefrom for engagement with said mechanisms for concomitantly actuating the latter.

16. In a multi-pole circuit breaker having a pair of circuit-breaker mechanisms each having a stationary contact, a movable contact member engageable and disengageable therewith and normally biased for movement from the circuit-closed to the circuit-open condition thereof, manually operable actuating means for effecting the engagement thereof, and a control member for effecting the disengagement thereof; said actuating means comprising a lever pivotally mounted on said contact member and releasably connected thereto by said control member in said circuit-closed condition, a link mounted for universal movement and retained against said movement in the circuit-closed condition of the circuit breaker by releasable engagement between said levers, a resilient member in which said link is

mounted for biasing said mechanisms in opposition to the bias thereon, said releasable engagement of said link and said levers including lost motion connections for said movement of said link upon release of one of said levers upon the occurrence of predetermined current in the circuit of the mechanism of said one lever whereby to relieve said opposing bias sufficiently for said circuit breakers to be moved to the circuit-open condition thereof, said levers having portions adapted for frictional engagement with their respective contact members for releasably retaining said levers in stationary position relative to their respective contact members, upon release of the latter to prevent free or uncontrolled movement of each actuator upon release thereof by its companion control member.

17. In a multi-pole circuit breaker having a pair of circuit-breaker mechanisms each having a stationary contact, a movable contact member engageable and disengageable therewith and normally biased for movement from the circuit-closed to the circuit-open condition thereof, manually operable actuating means for effecting the engagement thereof, and a control member for effecting the disengagement thereof; said actuating means comprising a lever pivotally mounted on said contact member and releasably connected thereto by said flexible member in said circuit-closed condition, a link mounted for universal movement and retained against said movement in the circuit-closed condition of the circuit breaker by releasable engagement between said levers, a resilient member in which said link is mounted for biasing said mechanisms in opposition to the bias thereon, said releasable engagement of said link and said levers including lost motion connections for said movement of said link upon release of one of said levers upon the occurrence of predetermined current in the circuit of the mechanism of said one lever whereby to relieve said opposing bias sufficiently for said circuit breakers to be moved to the circuit-open condition thereof, and a pair of casings each adapted to contain one of said circuit breaker mechanisms, respectively, said casings being disposed in surface abutting disposition, the abutting surfaces thereof being provided with aligned apertured portions, said link being disposed in said apertures and extending therefrom for said engagement thereof between said levers.

18. In a multi-pole circuit breaker having a pair of circuit-breaker mechanisms each having a stationary contact, a movable contact member engageable and disengageable therewith and normally biased for movement from the circuit-closed to the circuit-open condition thereof, manually operable actuating means for effecting the engagement thereof, and a control member for effecting the disengagement thereof; said actuating means comprising a lever pivotally mounted on said contact member and releasably connected thereto by said control member in said circuit-closed condition, a link mounted for universal movement and retained against said movement in the circuit-closed condition of the circuit breaker by releasable engagement between said levers, a resilient member in which said link is mounted for biasing said mechanisms in opposition to the bias thereon, said releasable engagement of said link and said levers including lost motion connections for said movement of said link upon release of one of said levers upon the occurrence of predetermined current in the circuit of the mechanism

of said one lever whereby to relieve said opposing bias sufficiently for said circuit breakers to be moved to the circuit-open condition thereof, said levers having portions adapted for frictional engagement with their respective contact members for releasably retaining said levers in stationary position relative to their respective contact members, upon release of the latter to prevent free or uncontrolled movement of each actuator upon release thereof by its companion control member, and a pair of casings each adapted to contain one of said circuit breaker mechanisms, respectively, said casings being disposed in surface abutting disposition, the abutting surfaces thereof being provided with aligned apertured portions, said link being disposed in said apertures and extending therefrom for said engagement thereof between said levers.

19. A multi-pole circuit breaker having a movable contact member for each pole, an actuator for each movable contact member, a control device for each movable contact member to connect the companion actuator releasably thereto and to disconnect the actuator from the companion movable contact member, means for moving the released contact member to circuit-interrupting position, and universal joint means interconnected between said actuators and operable upon release of one of said movable contact members from its actuator under the control of the control device at one pole to effect movement of a contact member at another of said poles to its circuit-interrupting position, said universal joint means including spring means acting on each movable contact member to provide contact pressure at each pole in the circuit-closed condition of the circuit breaker.

20. A multi-pole circuit breaker having a movable contact member for each pole, an actuator for each movable contact member, a control device for each movable contact member to connect the companion actuator releasably thereto and to disconnect the actuator from the companion movable contact member, means for moving the released contact member to circuit-interrupting position, and means interconnected between said actuators and operable upon release of one of said movable contact members from its actuator under the control of the control device at one pole to effect movement of a contact member at another of said poles to its circuit-interrupting position, said interconnected means including a lost-motion connection at each actuator so that movement of the released actuator at one pole is not impeded by a non-released actuator at another pole.

21. A multi-pole circuit breaker having a movable contact member for each pole, an actuator for each movable contact member, a control device for each movable contact member to connect the companion actuator releasably thereto and to disconnect the actuator from the companion movable contact member, means for moving the released contact member to circuit-interrupting position, and universal joint means interconnected between said actuators and operable upon release of one of said movable contact members from its actuator under the control of the control device at one pole to effect movement of a contact member at another of said poles to its circuit-interrupting position, said universal joint means including a lost-motion connection at each actuator so that movement of the released actuator at one pole is not

impeded by a non-released actuator at another pole.

22. A multi-pole circuit breaker having a movable contact member for each pole, an actuator for each movable contact member, a control device for each movable contact member to connect the companion actuator releasably thereto and to disconnect the actuator from the companion movable contact member, means for moving the released contact member to circuit-interrupting position, and universal joint means interconnected between said actuators and operable upon release of one of said movable contact members from its actuator under the control of the control device at one pole to effect movement of a contact member at another of said poles to its circuit-interrupting position, said universal joint means including a lost-motion connection at each actuator so that movement of the released actuator at one pole is not impeded by a non-released actuator at another pole, and said universal joint means also including spring means acting on each movable contact member to provide contact pressure at each pole in the circuit-closed condition of the circuit breaker.

23. A multi-pole circuit breaker having a movable contact member for each pole, an actuator for each movable contact member, a control device for each movable contact member to connect the companion actuator releasably thereto and to disconnect the actuator from the companion movable contact member, means for moving the released contact member to circuit-interrupting position, and means interconnected between said actuators and operable upon release of one of said movable contact members from its actuator under the control of the control device at one pole to effect movement of a contact member at another of said poles to its circuit-interrupting position, said interconnected means including a lost-motion connection at each actuator so that movement of the released actuator at one pole is not impeded by a non-released actuator at another pole, said lost motion connection comprising slots defined in the actuators in which parts of the interconnected means have limited movements.

24. In a circuit breaker having a movable contact member, an actuator therefor, a control device to connect the actuator releasably to said movable contact member and to disconnect the actuator therefrom upon overload, and means for moving said movable contact member to circuit-interrupting position upon release thereof by said actuator, that improvement which comprises provision for releasably engaging said actuator and said movable contact member upon said release of the latter upon overload for releasably retaining said actuator in stationary position relative to the movable contact member to prevent free or uncontrolled movement of the actuator when the control device releases the latter.

25. A multi-pole circuit breaker having a movable contact member for each pole, an actuator for each movable contact member, a control device for each movable contact member to connect the companion actuator releasably thereto and to disconnect the actuator from the companion movable contact member, means for moving the released contact member to circuit-interrupting position, and means interconnected between said actuators and operable upon release of one of said movable contact members from its actuators under the control of the control device at one pole to effect movement of a contact mem-

ber at another of said poles to its circuit-interrupting position, said interconnected means including a lost-motion connection at each actuator so that movement of the released actuator at one pole is not impeded by a non-released actuator at another pole, and means for releasably engaging each actuator and its companion movable contact member upon release of the latter to circuit-interrupting position thereof for releasably retaining said actuator in stationary position relative to the movable contact member to prevent free or uncontrolled movement of the actuator when the control device releases the latter.

PAUL M. CHRISTENSEN. 15
